UNITED STATES PATENT OFFICE.

FRANK HORNQUIST, OF MOUNT JEWETT, PENNSYLVANIA.

SLED.

1,090,152.

Specification of Letters Patent. Patented Mar. 17, 1914.

Application filed January 20, 1913. Serial No. 743,189.

To all whom it may concern:

Be it known that I, FRANK HORNQUIST, a citizen of the United States, residing at Mount Jewett, in the county of McKean and State of Pennsylvania, have invented certain new and useful Improvements in Sleds; and I do declare the following to be a full, clear, and exact description of the invention, such as will enable others skilled in the art to which it appertains to make and use the same.

This invention relates to improvements in sleds and more particularly to cross beams and runner supports for sleds.

The object of the invention is to provide a light, strong and durable device of this character which is also very cheap to manufacture.

With this and other objects in view, the invention consists of certain novel features of construction, and the combination and arrangement of parts as will be more fully described and claimed.

In the accompanying drawings: Figure 1 is a bottom plan view of a sled equipped with this improved cross beam and runner support; Fig. 2 is a transverse vertical section thereof; Fig. 3 is a perspective view of one of the improved cross beams and runner supports detached; Fig. 4 is a plan view of the blank from which the knee is constructed; Fig. 5 is a similar view with parts broken out for convenience in illustration of the cross beam; Fig. 6 is a detail longitudinal section of the runner support; Fig. 7 is a transverse section taken on the line 7—7 of Fig. 6; Fig. 8 is a similar view taken on the line 8—8 of Fig. 6; Fig. 9 is an end elevation of this improved runner support showing it connected with the sled.

In the embodiment illustrated a sled is shown in which the runners 1 thereof are preferably constructed of steel bars substantially T-shaped in cross section and extending parallel to one another being curved upwardly at their front ends in the usual manner, said front ends being connected by a cross bar 2. Side bars 3 are also connected at one end to the cross bar 2 and are supported on cross bars or beams 5 which also support a series of slats 4 which form the top or seat of the sled.

The cross bars or beams 5 are each preferably constructed from a single piece of sheet metal in the form shown in Fig. 5, which is bent to form a channel bar as

shown in Fig. 3, the side flanges being bent inwardly adjacent their reduced ends 6 and then bulged to form pockets 7 for engagement with the knees to be described. The reduced ends 6 of said cross beam are offset downwardly from the top of said beam to form seats for the longitudinal side bars 3 of the sled frame, said extensions being also apertured to receive fastenings elements 65 for securing them to said side bars and also to the knees as will be hereinafter described. This beam 5 is also provided with a plurality of longitudinally spaced apertures in the top thereof for receiving the 70 fastening elements which connect said beams with the slats 4 of the sled seat.

The knees 8 which support the ends of the cross beams 5 and connect them with the runners 1 are preferably constructed from the blank shown in Fig. 4 to adapt them to be made from small sheets of metal thereby economizing in the construction of said knees. The blank from which each knee is constructed comprises a body portion 8 having diverging arms 10 which are bifurcated at their free ends to form attaching lugs 11 and said arms 10 are folded longitudinally to position said lugs opposite each other and adapt them to straddle the 80 standing flange of the runner as shown in Fig. 2, said lugs being apertured as is also the flange of the runner to receive the fastening bolts which connect the free ends of the knee to the runner. The body portion 80 of the blank from which the knee is formed is also folded longitudinally to form an angle bar adapted to fit within one end of the beam 5, said knee blank being bent to conform to the shape of the beam end and 95 said blank having a reduced extension 12 which is also offset from the body portion of the blank and bent to conform to the shape of the extension 6 of the beam, the side flanges thereof fitting closely within the 100 side flanges of said extension 6 and having an aperture therein registering with the aperture in said extension 6, whereby the fastening elements which secure the side bars 3 of the sled frame to the beams also 105 pass through these extensions of the knees and securely hold it in engagement with the frame.

The arms 10 which, after being folded, converge toward their upper or inner ends 110 have their side flanges flared at their connection with the body portion of the knee.

The folded portion thereof is substantially U-shaped in cross section and is adapted to fit within the pockets 7 of the beam 5, the inbent portion of said beam fitting snugly against 5 the outer face of said arms and thereby securely holding the knee against longitudinal movement. The inner ends of the knees fit within the flanges of the beam and are secured to said beam by the fastening elements which connect said beam to the slats 10 4 of the sled as shown clearly in Fig. 1.

By forming the knees in the manner above described and fitting them snugly within the ends of the beams 5, it will be obvious 15 that these knees and beams when secured by the fastening elements to the sled side bars and slats will form rigid strong supports capable of withstanding more weight or strain than if the beams and knees were 20 constructed of a single piece of metal as the flanges of said beams and knees reinforce each other and form substantial strong connections capable of withstanding heavy strains.

25 While I have described my invention with more or less minuteness as regards details and as being embodied in certain precise forms, I do not desire to be limited thereto unduly any more than is pointed out in the 30 claims. On the contrary, I contemplate all proper changes in form, construction and arrangement, the omission of immaterial elements and substitution of equivalents as circumstances may suggest or render expedient.

35 I claim as my invention:

1. A cross beam and runner support for sleds comprising a sheet metal channel bar having pockets in the side flanges thereof, and diverging knees substantially U-shaped in cross section adapted to fit in said pockets, and means for rigidly securing said knees to said bar.

2. A cross beam and runner support for 45 sleds comprising a sheet metal channel bar having pockets in the side flanges thereof

and offset ends beyond said pockets, and knees shaped to fit in said channel bars and having diverging legs with members fitting in said pockets, said knees also having offset flanged ends fitting in the offset ends of said bar, and means for securing said knees and bar together. 50

3. A cross beam and runner support for sleds comprising a sheet metal channel bar having pockets in the side flanges thereof near opposite ends, the ends of said bars beyond said pockets being offset downwardly, knees formed of folded sheet metal bent to form diverging legs having their side flanges flared at their connection with the body portion of the knee, the folded portion thereof being adapted to project into said pockets and a body having a downwardly offset end to fit the offset end of said bar, and means for securing said knees and bar together. 60 65

4. A cross beam for sleds composed of a strip of sheet metal reduced at its opposite ends and bent to form side flanges, said reduced ends being offset, and knees fitting between said side flanges and having offset ends fitting the offset ends of the beam, and means for securing said knees and beam together. 70 75

5. A cross beam for sleds composed of a strip of sheet metal reduced at its opposite ends and bent to form side flanges, said reduced ends being offset, the side flanges of said beam having pockets at the 80 bases of said reduced ends, knees having projections fitting in said pockets and offset ends fitting the offset ends of said beam, and means for rigidly connecting said knees and beam. 85

In testimony whereof I have hereunto set my hand in presence of two subscribing witnesses.

FRANK HORNQUIST.
